UNITED STATES PATENT OFFICE.

FRANK A. MILLER, OF MONTGOMERY, ALABAMA.

ROTARY EXPLOSIVE-ENGINE.

1,153,169.

Specification of Letters Patent. Patented Sept. 7, 1915.

Application filed September 15, 1913. Serial No. 789,743.

To all whom it may concern:

Be it known that I, FRANK A. MILLER, a citizen of the United States, residing at Montgomery, in the county of Montgomery, State of Alabama, have invented a new and useful Improvement in Rotary Explosive-Engines, of which the following is a specification.

The primary object of this invention is 10 the production of an engine of that class wherein explosive discharges are employed as a source of continuous power, and wherein the explosive medium before ignition does not come in contact with the exhaust 15 gases or products of combustion.

The invention is adapted to produce an additional amount of power, with less fuel, less vibration and less weight than heretofore and because of its lessened weight and 20 simple construction can be constructed and also used more economically.

It has been found previous to the production of my invention that owing to difficulty in producing tight joints between the 25 cooperating moving members of the rotor, cylinder and valves, that engines of the rotary type have been inefficient in operation. This defect has been overcome by my invention.

30 This invention also by its novel construction permits of lubrication of its working parts effectively without difficulty.

It also more perfectly than any prior device removes back pressure due to the escape 35 of gases including inert gases and the residual products of combustion between the moving parts of the engine.

It further governs the supply of fuel according to variation in load and by its 40 novel construction is adapted to produce a succession of explosions, of any number desired during every revolution.

A further object is the production of an engine of the class set forth which is useful 45 in all applications to which internal combustion engines are usually applied.

It is especially applicable to automobile, marine and other uses where power is used, owing to the absence of excessive vibration, 50 light weight, simplicity of construction, economy in use, and also to its compact form.

This invention while light in weight has 55 a liberal allowance for strength and is economical in fuel consumption and space and

reliable in operation. A novel means of cooling the engine is also provided.

Further objects and advantages will be apparent from the following description, reference being had to the accompanying drawings forming part of this specification in which—

Figure 1 is a vertical section of my improved engine; Fig. 2 is a section taken on the line A—A of Fig. 1; Fig. 3 is a section 65 taken on the line B—B, Fig. 1; Fig. 4 is a section taken on the line C—C, Fig. 1; Fig. 5 is a section taken on the line D—D, Fig. 1; Fig. 6 is a view of my invention shown connected with a form of fuel supply apparatus; Fig. 7 is a plan of the lower face 79 of the head, and Fig. 8 is a section on the line E—E, Fig. 1.

In the drawings, F indicates a suitable base in the form of a case in which a vertical shaft 2 is journaled in the step bearing 2'.

G indicates an air pump of rotary type having its cylindrical casing 3 secured to the base F by bolts 4, and H indicates my improved rotary engine having the lower end 5 of its cylindrical casing secured upon the casing of the pump by bolts 6. The base and casings of the pump and engine are arranged vertically with the shaft 2 extending concentrically therethrough. It is however feasible with my invention to arrange these parts in other positions than vertical. The end 5 of the casing of the engine has an annular space 6' surrounding 80 the shaft and a peripheral horizontal flange 7 upon which is mounted the cylinder wall 8 having horizontal ribs 9 on its exterior for air cooling purposes. This cylinder may be water cooled if desired. The portion 5 thus forms the lower side or end of the cylinder. Upon the top of the cylinder wall 8 is secured a head piece 10, which also has an annular space 11 within its wall surrounding a centrally disposed opening 12 85 through which the shaft 2 passes. This head forms the upper side or end of the cylinder. The lower side 5 and head 10 are secured to the cylinder wall by bolts 13 or in any other suitable manner.

Within the cylinder chamber formed by the cylinder wall 8, the lower wall 14 of the head and the wall 15 of the lower side 5 is placed a rotor or driving runner I having, a hub 15' keyed or otherwise secured to 100 105 110

the shaft 2, radiating spokes 16 and a cylindrical body 17 co-axial with the shaft. The cylindrical body 17 carries upon its periphery a plurality of radiating impeller blades 18, (see Fig. 3) the tips of which have wear pieces 19, seated therein and pressing outwardly under pressure to form tight working joints between the impelling elements and the cylindrical wall of the cylinder. 5 Four impelling elements are illustrated upon the rotor equally spaced apart around its axis and located in the wall of the cylinder and spaced evenly around the axis thereof are a plurality of vertical valve chambers 20, 10 which are adapted by hollow rotary valves 21 seated therein to admit fuel such as gas, air or a mixture of air and hydrocarbon into the cylinder through communicating ports 22 and 23 respectively in the wall of the cylinder 15 and 23 respectively in the wall of the 20 valve and through the wall of the cylinder, there being an uneven number such as one less valve than there are impelling elements on the rotor. Consequently three valves are 25 illustrated in the apparatus disclosed for the purpose of coöperating with four impelling elements on the rotor. This uneven number of coöperating elements is adapted to produce a large number of explosions in the combustion chamber every revolution of the 30 rotor.

Located adjacent each valve in the wall of the cylinder is a swinging abutment 24 and adjacent each abutment and valve and in communication with the space or pocket 35 formed by the impelling elements in the cylinder is an igniter 25 (see Fig. 2) of the usual character such as an electric spark plug which is seated in the wall of the cylinder. The valves 21 and swinging abutments 40 are made to operate in synchronism with the rotation of the rotor by suitable valve operating mechanism to be hereinafter described. The function of the abutments is to place a dam between the impelling elements on the piston in the cylinder, so as to form pockets in the cylinder back of each impelling element into which the gas or hydrocarbon fuel is automatically injected and ignited and later expelled at suitable successive intervals during the rotation of the 45 rotor.

The rotor is formed with suitable exhaust ports 26, one being placed in advance of each impelling element and egressing upwardly through an outlet opening 27 in the top of the body of the rotor, the outlets for said exhaust being equally spaced apart around the axis of the rotor and adapted to communicate at even successive intervals 50 with three exhaust ducts 28 (see Fig. 7) which are evenly spaced apart around the axis of the head and communicate with a common exhaust chamber 11 in said head and a nozzle 29 (see Fig. 2) leading to the outer atmosphere from the side of the head. 55

Placed in the cylinder adjacent its upper and lower sides are two flat wear rings 30 and 31, which form guides between which the ends of the abutments 24 slide, the lower plate being pressed upwardly by expansion 70 springs 32, which are seated in openings 33 formed in the lower side 5 of the cylinder. Thus the wear plates are held tightly in contact with the ends of the abutments and form a tight joint irrespective of the 75 amount of wear which takes place. The inner faces of the wear plates are cut out to form recesses 33' in which the abutments swing the edge 34 of each of said recesses forming a back stop which defines the limit 80 of movement of the abutment, at substantially right angles across the space intervening between the body of the rotor and the side wall of the cylinder. The edge or shoulder of each recess 33' also assists in 85 forming a tight joint between the abutment and the wear plates, so that a tight pocket is adapted to be formed in the combustion space.

Each abutment has a slotted hub 35 seated 90 in an opening 35' formed in the side and ends of the casing, said hub fitting over a shaft 35" which is journaled in said ends. The shaft has a lug 35''' on its side engaging in the slot with said hub to turn the 95 abutment by said shaft. The upper end of each of the shafts extends through and above the upper side of the cylinder and has a crank arm 36 attached thereto. To the free end of said arm a coil spring 37 is fastened, whose function is to normally urge the abutments across the combustion chamber in the cylinder as will be hereinafter more particularly described. The hollow 100 rotary valve 21 seated in each valve chamber 20 and having a port 22 in its side in the form of a longitudinal slot is formed with an open lower end and a closed upper end (see Fig. 1), said lower end being 105 adapted to connect with a manifold 38 which communicates with all of the rotary valves and is fastened to the lower side 5 of the cylinder by bolts 39. This manifold has a fuel ingress pipe 40 which is adapted to supply any fuel desired to the engine 110 for operating it such as a mixture of air and gasoline or any other hydrocarbon.

The upper end of each of the valves 21 is provided with a stem 41 passing through and journaled in the upper side of the cylinder, and to this stem is secured a suitable crank arm 42, having a suitable valve actuating mechanism to be hereinafter described connected to its free end, whereby the valves and the abutments are adapted to be operated in synchronism with the revolution 120 of the engine rotor. Each of the four impelling elements on the rotor is formed with an inwardly and forwardly sloping cam surface 43 which as the rotor revolves 125

ture disclosed. As the rotor revolves the perforations in the head plate 14 register with the ports 27 and relieve any pressure back of the impelling elements by conducting through ports 26 compressed gases and the products of combustion from back of the abutments. The governor controls the amount of fuel fed by the valves according to the speed of the rotor determined by the load. During this operation the air pump draws cool air down through the rotor and compresses it in the air pressure tank thus cooling the inner surfaces of the engine and storing air for use in preparing compressed fuel for operating the engine.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A rotary engine comprising in combination, a casing, a rotor within said casing and forming therewith an annular chamber, spaced impelling elements carried by said rotor, pivoted means disposed within said chamber adapted to coöperate with said impelling elements to form pockets, wear plates tensionally engaging said pivoted means for guiding and limiting the movement thereof in one direction, valved fuel inlets adapted to communicate with each of said pockets, means for operating said valved inlets to deliver into said pockets, means for igniting the fuel in each pocket, and exhaust ports for the spent gases.
2. A rotary engine comprising, in combination, a casing, a rotor within said casing and forming therewith an annular chamber, spaced impelling elements carried by said rotor, pivoted means disposed within said chamber adapted to coöperate with said impelling elements to form pockets, wear plates tensionally engaging said pivoted means for guiding the movements thereof, a backstop on said wear plates for limiting the movement of said pivoted means in one direction, means for normally holding said pivoted means against said backstop, valved fuel inlets adapted to communicate with each of said pockets, means for operating said valved inlets to deliver into said pockets, means for igniting the fuel in each pocket, and exhaust ports for the spent gases.
3. In a rotary explosive engine, the combination of a cylinder, a rotor co-axial with said cylinder forming a chamber and having a plurality of impelling elements on its periphery, a plurality of swinging abutments seated in the wall of said cylinder and pivoted therein so as to swing across said chamber and assist in forming pockets in which compressed fuel is received and fired, the number of abutments being different from the number of impelling elements on said rotor, said impelling elements being formed with inwardly and forwardly sloping faces which are adapted to sweep over said abutments and swing them out of their path, means for returning said abutments across said chamber immediately back of the impelling elements, a valve in the wall of said cylinder communicating with each of said pockets and adapted to admit fuel therein the valves being of uneven number as regards the number of impelling elements on said rotor, means for firing the fuel in each of said pockets, said rotor being formed with an exhaust passage leading from in front of each impelling element and terminating through the end of said rotor and an end plate on said cylinder having port openings with which said exhaust passages are adapted to register to exhaust spent gases from the pockets and having perforations which are adapted to register with said port passages to release gases remaining in front of the impelling elements and back of said abutments across said chamber.
4. In a rotary explosive engine, the combination of a cylinder, a rotor co-axial with said cylinder forming a chamber and having a plurality of impelling elements on its periphery and exhaust passages from said chamber from in front of said impelling elements and through the rotor's end, a plurality of abutments pivoted in the wall of said cylinder and adapted to swing across said chamber and assist in forming a series of pockets and to move back out of the path of said impelling elements, said chamber having a plurality of valved inlets for compressed fuel into said series of pockets, means for firing the fuel in said pockets and a pair of spring pressed wear rings having seats in which the ends of said abutments are adapted to turn and stop shoulders defining the position of said abutments across said chamber, said rings being held tight upon the opposite ends of said abutments to produce gas tight joints.
5. A rotary engine comprising, in combination, a casing, a shaft extending through said casing, a rotor keyed upon said shaft and forming with said casing an annular chamber, spaced impelling elements carried by said rotor, a plurality of swinging abutments disposed within said chamber and adapted to coöperate with said impelling elements to form pockets, valved fuel inlets adapted to communicate with each of said pockets, a driving collar carried by said

shaft and having cam surfaces, mechanism connected with said valved inlets and adapted to be tripped by said cam surfaces for operating said valved inlets to deliver into 5 said pockets, means actuated by said shaft to frictionally engage said collar for automatically governing the movements of said valved inlets to regulate the amount of fuel delivered into said pockets, means for igniting the fuel in said pockets, and exhaust ports for the spent gases.

6. In a rotary explosive engine, the combination of a cylinder, a rotor co-axial with said cylinder forming a chamber and having a plurality of impelling elements on its periphery formed with forwardly and inwardly sloping surfaces and abrupt rear walls, said cylinder and rotor being formed respectively with admission and exhaust 15 ports, a plurality of abutments pivoted in the wall of said cylinder and adapted to swing across into said chamber pocket forming position, the number of said abutments being different from the number of said impelling elements so as to produce a succession of pockets every revolution of the rotor, springs normally urging said abutments into pocket forming position, the front surfaces of said impelling elements being 20 adapted to sweep said abutments into the wall of said cylinder and the back surfaces to release said abutments into pocket forming position, spring pressed wear rings having recesses in which the ends of said abutments are slidably seated and forming shoulders defining the pocket forming position of said abutments, and means for firing the fuel admitted into said pockets.

7. In a rotary explosive engine, the combination of, a cylinder, a rotor co-axial with said cylinder forming a chamber and having a plurality of impelling elements on its periphery, said cylinder and rotor being formed respectively with admission and exhaust 40 ports, a plurality of abutments pivoted in the wall of said cylinder and adapted to

swing across said chamber into pocket forming position, the number of said abutments being different from the number of said impelling elements so as to produce a succession of pockets every revolution of the rotor, a plurality of open ended cylindrical valves rotatively seated in said cylinder to connect with said admission ports and admit fuel under pressure into said pockets, a 50 manifold connecting with the open ends of said valves and means for igniting the charges of fuel in said succession of pockets.

8. In a rotary explosive engine, the combination of, a cylinder, a passaged rotor co-axial with said cylinder forming a chamber and having a plurality of impelling elements on its periphery, said cylinder and rotor being formed respectively with admission and exhaust ports, a plurality of abutments pivoted in the wall of said cylinder and adapted to swing across said chamber into pocket forming position, the number of said abutments being different from the number of said impelling elements so as to produce a 55 succession of pockets every revolution of the rotor, a plurality of valves seated in said cylinder to communicate with said admission ports and admit fuel under pressure into said pockets, a fuel and air mixer connected with said valves, a fuel chamber connected with said mixer, means for igniting charges of fuel in said succession of pockets, an air compressor mounted co-axial with said rotor having its inlet adapted to exhaust air from the passage through said rotor and cool its surfaces, and a pressure tank connected with the air pressure outlet from said compressor and with said fuel tank and mixer.

In testimony whereof, I have signed my name to this specification, in the presence of two subscribing witnesses.

FRANK A. MILLER.
